(57) **CLAIM**

The ornamental design for an optical fiber connector as shown and described.

DESCRIPTION

1. Optical fiber connector

1.1 is a front, top, right side perspective view of an optical fiber connector;

1.2 is a front elevation view thereof;

1.3 is a back elevation view thereof;

1.4 is a top plan view thereof;

1.5 is a bottom plan view thereof;

1.6 is a left side elevation view thereof;

1.7 is a right side elevation view thereof;

1.8 is a cross-sectional view taken along line A-A' of reproduction 1.2; and,

1.9 is a cross-sectional view taken along line B-B' of reproduction 1.3.

The claim is directed to an optical fiber connector, used for holding a ferrule and connecting optical fibers. The dash-dot broken lines in the reproductions illustrate portions of the article that form no part of the claimed design. The dot-dot broken lines in the reproductions illustrate boundaries of the claim and form no part of the claimed design. The dot-dot broken line arrows and letters in 1.2 and 1.3 are for annotative purposes only and form no part of the claimed design.
